LOUIS ERRANI AND LOUIS GUÉRIN, OF PARIS, FRANCE.

ROTARY MOTOR.

No. 833,081.

Specification of Letters Patent.

Patented Oct. 9, 1906.

Application filed May 31, 1905. Serial No. 262,998.

To all whom it may concern:

Be it known that we, LOUIS ERRANI, a resident of 14 Rue Clauzel, and LOUIS GUÉRIN, a resident of 47 Rue Ramey, Paris, France, 5 citizens of the Republic of France, have invented an Improvement in Rotary Motors, of which the following is a specification.

This invention relates to a rotary motor comprising a plurality of cylinders secured 10 for rotation about a common axis and each containing a weight and means for moving said weights to cause displacement of the center of gravity.

In the illustrated embodiments of our invention a plurality of cylinders containing heavy weights are arranged at regular intervals around the axis of the motor, with each cylinder extending in both directions for a considerable distance beyond said axis, and 15 connections are provided whereby each weight is raised by pressure when the end of the cylinder containing it reaches the lowest point of travel, the raised weight being moved to the then upper end of the cylinder 20 and above the axis of the motor.

In the accompanying drawings, Figure 1 is a cross-section of one form of motor embodying our invention. Fig. 2 is a longitudinal section of such form of motor, and Fig. 3 25 especially illustrates details of the valves for controlling supply of pressure to the cylinders and exhaust thereof.

The frame supporting the motor may comprise uprights *ll*, which non-rotatively support the aligned axles *X*. A motor-body, such as cylinder *m*, is mounted to rotate concentrically around the axles *X*. At one end said body is shown as rigidly and adjustably secured by screws *g* to a bored block *Z*, 30 surrounding a sleeve upon the short axle *X*, and at its other end the body *m* is rigidly and adjustably secured, also by screws *g*, to a tube *h*, surrounding two rings arranged end to end and one of which, *k*, is secured against rotation, the other ring moving with the tube *h*. 35 Both rings surround a sleeve upon the longer axle *X*.

The body *m* is provided with cylinders *a*, *b*, *c*, and *d*, of cast-iron or other material, and 40 arranged, preferably, at regular intervals around and longitudinally of the cylinder. Each cylinder extends through and projects at both ends for a considerable distance from the body *m*, and each cylinder is provided

with an opening or port at each of its ends, 55 and each port communicates with a pipe or tube. The various pipes just referred to pass through the tube *h* and lengthwise of the ring rotating with said tube.

Freely-slidable weights *f*, *f'*, *f''*, and *f'''* are 60 fitted one within each of the cylinders *a*, *b*, *c*, and *d*. Said weights may be of any material, such as solid or hollow castings. If hollow, they may be entirely or partly filled with lead, or even mercury. In the instance illustrated 65 each weight is about half the length of the cylinder wherein it works, though such proportions are optional.

The ring *k*, secured against rotation as aforesaid, is provided with a supply-pipe *i* 70 and an exhaust-pipe *e*, the former being connected with a cock *v*, leading from the source of steam, gas, or other pressure. The ports in the ring *k*, from which the pipes *i* and *e* lead, are, as shown in Fig. 3, slightly elongated. 75

In the operation of the motor illustrated the cylinders *a*, *b*, *c*, and *d* are successively presented at the lowest point of their travel, with the weights *f*, *f'*, *f''*, *f'''* in the ends thereof 80 then lowermost, and at or near the point mentioned pressure is supplied to the cylinders, so as to shift or lift the weights to the ends of the cylinder then uppermost, the proper supply and exhaust connections being established. As shown in Fig. 2, when the pipes connected with the respective ends of a cylinder come into register with the pipes in the fixed ring *k* pressure passes by way of pipes *i* into the lowermost end of cylinder *a*, 85 and the weight *f* is raised or forced to the uppermost end of the cylinder, from which air or other medium is exhausted by way of pipes *e*. The same is true of each of the cylinders as it reaches the point mentioned, and 90 as the weights are raised every time they reach the lowermost point of their travel, it follows that (with the motor illustrated) there will always be a preponderance of the weights at one side of the axis of 95 the motor as long as pressure is supplied and rotation of the motor will continue.

It will be obvious that the pipes entering the opposite ends of the cylinders *a*, *b*, *c*, and *d* serve alternately as a supply-pipe and as an 100 exhaust-pipe.

What we claim is—

In a rotary motor, a cylindrical rotata-

ble motor-body, a plurality of cylinders extending through and projecting at both their ends from said body, and arranged at intervals around and longitudinally of said body, slideable weights within the second-named cylinders, and connections for causing the weights within the cylinders to shift above the axis of the body.

In testimony whereof we affix our signatures in presence of two witnesses.

LOUIS ERRANI.
LOUIS GUÉRIN.
